UNITED STATES PATENT OFFICE.

JOHN F. CLASS, OF DAYTON, OHIO

MEDICINAL-VAPOR GENERATOR.

1,262,638.

Specification of Letters Patent. Patented Apr. 16, 1918.

Application filed July 5, 1917. Serial No. 178,647.

To all whom it may concern:

Be it known that JOHN F. CLASS, a citizen of the United States, residing at Dayton, in the county of Montgomery and State 5 of Ohio, has invented certain new and useful Improvements in Medicinal-Vapor Generators, of which the following is a specification.

My invention relates to new and useful 10 improvements in medicinal vapor or fume generating apparatus. The object and purpose of the invention is broadly to provide a medicinal vapor or fume generator which has a facility for applying the medicinal vapors or fumes to selected portions 15 of the human body which it may be desired to treat. To this end the invention consists of a medicinal vapor or fume generator, a distributing drum into which the product 20 is discharged from said generator, and a cabinet into which the vapor is discharged from the distributor through an arrangement of a multiplicity of conduits or pipes and is applied to selected parts of the body 25 as will hereinafter more fully appear from the particular description and the accompanying drawings to which the description relates.

Referring to the accompanying drawings 30 in general terms Figure 1 is an elevation of the apparatus in its entirety. Fig. 2 is a side elevation of the cabinet and the conduits leading thereto, a portion of the cabinet being broken away to illustrate the various appliances within it. Fig. 2^a is a vertical elevation of the main vapor or fume generator showing the arrangement of the various vaporizing pans on the interior thereof. Fig. 3 is a top plan view of Fig. 40 2 with a portion of the top of the cabinet broken away and with the side conduits leading to the cabinet omitted. Fig. 4 is a detailed view of the telescopic adjustable feature of the tubes entering the cabinet. Fig. 45 5 is a detailed view of the cabinet slides which seal or inclose the cylinders or larger conduits at the point of their entrance into the cabinet. Fig. 6 is a detailed view of the seat within the cabinet. Fig. 7 is a detailed view of the head rest.

In a more particular description of my improved medicinal vapor or fume applying apparatus, similar reference characters indicate corresponding parts of the apparatus 55 in the description and the drawings. As hereinbefore stated the apparatus is de-

signed to generate and apply medicinal vapors or fumes to various parts of the human body such as the limbs, the torso, the head, etc. The main vapor or fume generator is 60 shown in detail in Fig. 2 of the drawings and consists of an up-right rectangular casing preferably constructed of suitable sheet metal with a hinged door 2 in the front and a damper 3 in the rear. Within the base 65 of this casing is arranged a hydro-carbon burner 4, which is fed through a pipe 5 and is supplied with air through a suitable number of openings 6. Above the burner 4 a water pan 7 is located, and above this 70 water pan 7 is located a shallow water pan 8. These water pans 7 and 8 furnish the vapor to be passed over a series of mineral-containing receptacles, which results in the medicinal fumes to be applied. These mineral-containing receptacles 9, 10, 11, 12 and 13 are of a shallow construction and are arranged in a zigzag manner so that the vapor or fumes passes over them from one side to the other as is clearly indicated by 75 the several arrows. Upon the top of the casing 1 is arranged a contracted casing 1' into which the medicinal vapor is discharged from the main generator 1. The contracted or smaller casing 1' has a removable cover 14 on one side and within said casing is arranged a suitable number of shallow mineral-containing pans 15. The arrangement of pans thus described are supported on shelves suitably arranged and 80 these pans may be removed and replaced when desired through the doors of the casing. The medicinal vapors are conducted from the main generator through a suitable number of pipes or conduits 16 to an auxiliary generator 17, which is shown on an upper floor 18 of the building in which the apparatus is installed. One of these distributing pipes or conduits 16 may conduct 85 the vapor to another auxiliary generator 90 arranged on a lower floor of the building or at any suitable point. Within the auxiliary generator 17 may be arranged a suitable number of mineral-containing pans 95 similar to their arrangement in the main generator. It will be understood the temperature of the vapor or fumes as they enter the auxiliary generator 17 are somewhat reduced in temperature and it is designed that the vapor or fumes generated within the 100 auxiliary generator 17 shall be still somewhat reduced to the requisite temperature. 105 110

Experience and practice has demonstrated that much efficiency is due in the application of the medicinal vapors or fumes when applied at the proper temperature and this arrangement of vapor or fume generators is designed to regulate and maintain this proper temperature. From the auxiliary generator 17 the vapor or fumes may be piped to any suitable number of cabinets 19 through pipes 20. The pipes 20 at each cabinet enters a distributing drum 21 from which the vapor or fumes are distributed to various points within the cabinet 19 for application to the parts of the patient it is desired to treat. Within the base of the cabinet 19 is arranged a cylinder 22 which is supported upon casters and is movable with or independently of the cabinet as the case may require. This cylinder is provided at its top with an apertured seat 23 upon which the patient sits in the treatment of rectal complaints and a back-rest 24 is provided for the comfort of the patient when occupying this seat. The medicinal vapor or fumes are conducted into the cylinder 22 below the seat 23 through side conduits 25 which extend from the distributing drum 21. The medicinal vapor is conducted into the lower portion of the cabinet 19 through side conduits 26 which also extend from the distributing drum 21. It will thus be seen that a patient sitting upon the seat 23 may be treated by the application of the medicinal vapor to particular parts of the body. Inclosures are also provided for the reception of the legs and arms of the patient when it is desired to treat these members alone or separately. This means consists of two cylinders 27 which extend into the upper portion of the front of the cabinet and may be adjusted in and out through a telescopic arrangement with an outer cylinder 28, as shown in Fig. 4. The outer cylinder 28 is supported on a stand 29 and is therefore stationary. The stand 29 has suitable seats 30 at its upper end in which the cylinder 28 is supported. The telescopic connection between the cylinders 27 and 28 is properly sealed so that the vapor or fumes are wholly discharged into the cylinders. It will be understood that there is one of these telescopic cylinders arranged for each arm and the vapor or fumes are conducted thereto from the distributing drum 21 through pipes 31. On the inner ends of the cylinders 27 a flexible inclosure 32 is arranged with a draw-string 33 by which said flexible inclosure may be drawn tight around the arm to prevent any of the vapor or fumes escaping, it being desirable to apply the full effect of the vapor or fumes to the portion of the arm extending into the cylinder 27. There are similar cylinders 34 extending into the lower portion of the front of the cabinet for the reception of the

legs in the treatment of the legs or lower limbs of the patient. These cylinders 34 are associated with telescopic cylinders 35 both of which are arranged on the incline shown in Figs. 2 and 3 of the drawings. The outer cylinders 35 are supported on the stand 29 in a manner similar to the cylinders 28. The cylinders 34 and 35 receive the mineral vapor from the distributing drum 21 through conduits 36 and the inner projecting ends of the cylinders 34 are provided with flexible inclosures 32 which have draw-strings 33 by means of which they are drawn tightly around the legs in a manner similar to the arms. The conduits 31 and 36 extending into the arm and leg cylinders are provided with openings through which mineral substance may be introduced through funnel-shaped feed devices 37 when it is desired to increase the strength of the vapor or fumes entering said cylinders. The distributing drum 21 and the conduits 26 are firmly supported on suitable stands 38. The arm and leg cylinders 27 and 34 at the points where they enter the cabinet are provided with slides 39 which move in guides 40 on the outside of the front of the casing. These slides 39 provide the necessary opening for the cylinders and fit snugly around said cylinders to seal the entrance of said cylinders into the cabinet, it being desirable to permit of no appreciable escape of the vapor or fumes discharging into the cabinet. The top of the cabinet 19 has a suitable opening 41 through which the head of the patient projects, and above this opening and in a suitable position to inclose the head of the patient, is arranged a hood 42 of suitable flexible material that may be provided with a draw-string to hold the same tightly in position. This device is intended for the application of the medicinal vapor to the head of the patient and the hood 42 is supplied with vapor from the distributing drum 21 through a conduit 43 which communicates with an up-right conduit 44 at the rear of the cabinet, said up-right conduit 44 having the hood 42 attached thereto. On the interior of the hood is arranged straps 45 which serve to prevent the hood from being drawn too far over the head. Valves or dampers 47 are arranged at convenient points in the conduits for the purpose of controlling the distributing of the fumes.

From the foregoing description, it will be seen that the medicinal vapor is so controlled that it may be applied to various parts of the human body where local treatment of this character is required and excluded from other parts. It will further be seen that the vapor or fumes may be concentrated upon any particular part or applied to all parts simultaneously. The

vapor or fumes may be excluded from the cabinet when it is not desired to apply it to the body, and may be applied to the arms or other parts alone. The arrangement is such that the fumes may be varied and the application thereof may be controlled in effecting desirable results.

Having described my invention, I claim:

1. In an apparatus of the character specified, the combination with a medicinal vapor or fume generator, of a cabinet adapted to receive the patient to be treated, a distributing drum to which the vapor or fumes are conducted from the generator, conduits extending from the distributing drum to the cabinet through which said vapor or fumes are conducted to said cabinet, telescopic cylinders adapted to receive the limbs of the patient within the cabinet, sealing devices on the portions of said cylinders within the cabinet adapted to confine the vapor to the portions of the limbs within said cylinders, and conduits extending from said distributing drum to said tele-

scopic cylinders, whereby the vapor or fumes may be applied to selected parts of the patient.

2. In an apparatus of the character specified, the combination with a vapor or fume generator, of a cabinet designed to receive a patient to be treated, a distributing drum receiving the vapor or fumes from said generator, a conduit extending between said distributing drum and the cabinet, telescopic cylinders extending into the cabinet and adapted to receive the limbs of the patient to be treated, flexible sealing devices attached to the telescopic cylinders within the cabinet and adapted to confine the vapor to the portions of the limbs lying within said cylinders, conduits extending from the distributing drum to said telescopic cylinders, a hood adapted to receive the head of the patient, and a conduit extending from the distributing drum to said hood.

In testimony whereof I affix my signature.

JOHN F. CLASS.
